BY

ATTORNEY

UNITED STATES PATENT OFFICE.

ALFRED CONRAD R. JOHNSDORF, OF SEATTLE, WASHINGTON.

PADLOCK.

1,253,249.

Specification of Letters Patent. Patented Jan. 15, 1918.

Application filed July 25, 1917. Serial No. 182,774.

To all whom it may concern:

Be it known that I, ALFRED CONRAD R. JOHNSDORF, a citizen of the United States, residing at Seattle, in the county of King 5 and State of Washington, have invented certain new and useful Improvements in Padlocks, of which the following is a specification.

This invention relates to new and useful 10 improvements in pad locks and the principal object of the invention is to provide means whereby the same can be unlocked without the use of a key.

Another object of the invention is to provide 15 the lock with a key hole to indicate to an unauthorized person that the lock is of the ordinary type, to be opened with a key so as to detract his attention from the real operation of the lock.

Another object of the invention is to provide 20 means for preventing the shackle being removed by the removal of the pivot pin thereof.

Another object of the invention is to provide 25 a device of this character, which is simple and durable in construction, reliable and efficient in operation and one which can be manufactured and placed upon the market at a minimum cost.

The invention also consists in certain 30 other features of construction and in the combination and arrangement of the several parts, to be hereinafter fully described, illustrated in the accompanying drawing 35 and specifically pointed out in the appended claim.

In describing my invention in detail, reference will be had to the accompanying drawings, wherein like characters denote 40 like or corresponding parts throughout the several views, and in which:

Figure 1 is a sectional view of the invention.

Fig. 2 is a like view taken at right angles 45 to Fig. 1.

Fig. 3 is a sectional view on line 3—3 of Fig. 1.

Fig. 4 is a bottom view.

In these figures 1 indicates the casing of 50 the lock, preferably of oblong shape and having its bottom 2 removably secured in place by the screws 3. 4 indicates the shackle pivoted in the upper part of the case by means of the pin 5 and the other end of this 55 shackle is adapted to enter an opening 6 in the case. 7 indicates a member having one

end formed with or connected to the pivoted end of the shackle so that said member is moved whenever the shackle is moved. This member is provided with an enlarged lower 60 end having a heel part 8 for limiting the backward movement of the member and a toe part 9 having a right angular extension 10 thereon. 11 indicates a member having a cylindrical lower end 12 projecting from an opening 13 in the bottom 2, and this end is provided with a key hole 14 which passes entirely through this part. The said member 11 has a rectangular upper part 15, one of the flat sides of which engages one side of the casing to prevent rotary movement of the member, and at the opposite side said member is provided with an inclined face 16 having a square recess 17 at its lower end adapted to receive the 75 projection 10 on the member 7. The member 11 is provided with a stem 18 connected to its upper end and passing through an opening 19 in the upper part of the casing and a spring 20 is carried by this stem and 80 lies between the member 11 and the top of the casing, so that the member 11 is normally held with its cylindrical end projecting from the bottom of the casing and with the recess 17 engaging the projection 10. 85

21 indicates a leaf spring connected with the pin 5 and engaging the lower part of the member 7 to swing said member upwardly to open the shackle. 22 is a nose formed on the casing right above the heel 90 8 to prevent the member 7 from being lifted by first removing the pin 5. 22' is another nose below the heel.

With the parts in the position shown in Fig. 1, that is with the shackle closed, the 95 member 11 will prevent the shackle being opened as the projection 10 on member 7 is in engagement with the recess 17 and thus the member 7 is held against movement.

When it is desired to unlock the device, 100 the cylindrical part 12 is pressed inwardly so as to force the member 11 with its stem toward the top of the casing, thus raising the recess 17 above the projection 10 so as to permit the spring 21 to swing the member 105 7 forwardly and thus raise the shackle. In this movement the toe 9 with the projection 10 will pass between the inclined face 16 and the top of the cylindrical part 12. When the cylindrical part is released the 110 spring 20 will cause the member 11 to move downwardly and the inclined face 16 will

engage the projection 10 and thus prevent the member 7 from being pushed back to its original position and thus the shackle is kept open. When it is desired to close the shackle again the same is pushed inwardly thus causing the projection 10 to engage with the inclined face 16 to force the member 11 upwardly to allow the member 7 to assume its normal position when the member 11 will be forced by the spring downwardly and the recess 17 will engage with the projection 10.

If an unauthorized person should attempt to open the lock with a key, the key would pass through the key hole and strike the toe 9 and projection 10 and thus prevent the member 11 being moved upwardly.

If he should attempt to open the lock by removing the pin 5 he would be prevented from opening the shackle by reason of the fact that the member 7 is still held from being lifted up by means of the nose 22 engaging with the heel 8.

While I have shown the casing with its sides formed integral and only the bottom detachable I do not wish to be limited to this construction as I may make the sides detachable as well as the bottom.

It is thought from the foregoing that the

advantages and novel features of my invention will be readily apparent.

I desire it to be understood that I may make slight changes in the construction and in the combination and arrangement of the several parts, provided that such changes fall within the scope of the appended claim.

I claim as my invention:

A padlock including a casing, a shackle pivoted therein, an extension on the shackle beyond the pivotal point projecting into the casing, a slid able barrel having a key opening therein, a lateral lug on said barrel having an inclined face and a recess at the end of said inclined face, a lug on the extension to enter the recess, a spring engaging the barrel to retain said lug in the recess, the lug of the extension being engageable by the key when inserted in the barrel to prevent unlocking of the lock, and a lug in the casing engaging the extension to assist in retaining the shackle in locked position.

In testimony whereof I affix my signature in presence of two witnesses.

ALFRED CONRAD R. JOHNSDORF.
